ABSTRACT

A method of preparing a package of flexible molding strips for display in an aesthetic manner, which includes the steps of reproducing by silk screening or similar process, a repeating pattern on a large sheet of flexible fibrous or plastic material carrying a pressure sensitive adhesive on one side thereof, with the pattern being repeated in elongated strips on the substrate; then severing the substrate along a plurality of relatively short lines by the use of die rule press knives pressed against the substrate, and concurrently severing the substrate along a pair of relatively longer elongated lines lying to the outside of the relatively short lines of severance to provide a plurality of short lines of severance between a pair of relatively long lines of severance in the substrate; repeating the pattern of a plurality of short lines of severance located between long lines of severance over the entire areal extent of the substrate with all the lines of severance extending substantially parallel to each other, and with the lines of severance being formed between the lines of the decorated figures imprinted on the substrate by the silk screening process. A plurality of the superimposed substrate sheets are then severed along a pair of lines extending normal to the first mentioned lines of severance and positioned adjacent side edges of the substrate at a location such that the pairs or lines of severance adjacent the side edges of the superimposed substrate sheets intersect the relatively long lines of severance previously formed so as to free from each other, portions of the substrate which contain formed between side edges previously constituted by the relatively long lines of severance, a plurality of strips which are separated from each other by the relatively short lines of severance.

METHOD OF FORMING A PACKAGE OF FLEXIBLE MOLDING STRIPS

BACKGROUND OF THE INVENTION

1. Field of the Invention

This invention relates to a method of forming a package of decorative flexible strips useful as a molding, the packages as formed including a plurality of easily separable strips joined together by transverse web portions which interconnect opposite ends of the strips.

2. Brief Description of the Prior Art

It has been heretofore known to provide strips of flexible fibrous or plastic material upon which a decorative pattern has been imprinted by some suitable process, which strips carry a pressure-sensitive adhesive on one side thereof, and which can be placed on the edges of cabinet work, furniture, and the like to provide a decorative molding. When in place, the molding strip appears to be a portion of the furniture or base material to which the molding strip is applied. These strips have frequently been supplied in rolls, or in packages in which the strips are superimposed upon each other.

BRIEF DESCRIPTION OF THE PRESENT INVENTION

This invention relates to a method of preparing packages of decorative molding strips made of a fibrous or plastic flexible material, which strips carry a decorative repeating pattern on one side thereof and which are provided with a pressure-sensitive adhesive on the other side thereof which permits the strip to be adhered to a wood or other rigid supporting surface. The packages as manufactured by the method of the present invention, permit a very aesthetic display of the strips which enhances sales of the packages, and permits a more profitable marketing of strips of this general type than has been possible with molding strips of this type as they have been previously packaged for the market.

Broadly described, the method of the present invention comprises initially imprinting, by a process such as silk screen printing, a flexible fibrous or plastic substrate sheet material with a series of longitudinally aligned repeating figures, so that the appearance of one side of the flexible substrate material is that of a series of juxtaposed strips identified by the alignment of repeating figures on each strip. After the completion of the printing process, a number of sheets of the substrate material, each having a pressure-sensitive adhesive on the opposite surface thereof from that which carries the printing, are superimposed upon each other, and are subjected to a slitting process using die rule cutting surfaces mounted either in a flat bed press or in a rotating drum press of any suitable type well known in the art. The arrangement of the cutting edges in the die rule press is such that a plurality of relatively short cutting edges are positioned between a pair of relatively longer cutting edges. When the superimposed or stacked substrate sheets are slit through by the use of the die rule press made up in the manner described, the substrate sheets are cut through or severed along a plurality of parallel lines which extend less than the full width of the sheets, and this results in parallel slits being formed in the sheets between the outer edges thereof.

Due to the make-up of the die rule cutting edges employed, the pattern of slitting which is accomplished in this manner includes a plurality of pairs of outside slits which are relatively long, and which bound or lie to the outside of a plurality of relatively shorter slits which are spaced evenly with respect to each other and with respect to the outside slits. There are thus formed a plurality of strips within each of the substrate sheets, with these strips being contiguous and joined at their opposite ends by web portions which extend transversely of the substrate sheet, and normal with respect to the longitudinal axes of the several strips. The relatively long boundary slits do not extend completely through this adjoining web portion of the substrate sheets.

After the slitting process by the use of the die rule press has been accomplished, the stacked or superimposed substrate

sheets are then subjected to a transverse cutting procedure using a guillotine blade, or similar cutting device, to cut through the web portions of the stacked sheets in such a way that the relatively long slits formed in the sheets are intersected by the cut made by the guillotine blade. The result of this cutting operation is to separate a plurality of series of joined strips which have the same repeating pattern on each strip in each series, and to thereby provide an attractive package of contiguous elongated strips suitable for use as a molding when applied in a manner well understood in the art.

An object of the invention is to provide a method or process for quickly and easily making an attractive package of easily separated, elongated molding strips which carry a pressure-sensitive adhesive on one side thereof, and which can be easily used by a purchaser to provide a decorative molding on articles of furniture and the like.

Another object of the invention is to improve the aesthetics of packaging elongated flexible molding strips made of a fibrous material and carrying a pressure-sensitive adhesive on one side thereof.

Additional objects and advantages of the invention will become apparent as the following detailed description of the invention is considered in conjunction with the accompanying drawings.

BRIEF DESCRIPTION OF THE DRAWINGS

FIG. 1 is a sectional view taken through a die rule press made up for the purpose of practicing the process of the present invention.

FIG. 2 is a plan view of a portion of the die rule press made up in the manner illustrated in section in FIG. 1, and useful in the practice of the process of the present invention.

FIG. 3 is a plan view of a fibrous substrate which has been imprinted with a decorative pattern, and which has been cut or slit with a die rule press of the type depicted in FIG. 2 in one of the intermediate steps in the practice of the process of the present invention.

FIG. 4 is a plan view of the package which is produced as a final product of the process of the present invention.

DESCRIPTION OF THE PREFERRED EMBODIMENT OF THE INVENTION

Referring initially to FIGS. 1 and 2 of the drawings, shown therein is a die rule press made up for utilization in the practice of the process of the present invention. The use in the graphic arts technology of die rule presses for cutting through fibrous and synthetic resin substrate materials to achieve certain patterns and configurations according to the manner in which the substrate is cut is well known. In general, a die rule press is made up similarly to a font of type utilized in printing, and includes, in the illustrated form as shown in FIGS. 1 and 2, a plurality of spacer blocks 10 and a metallic backing plate 12 which are used to position, and to set in a desired configuration, a plurality of blade elements 14 and 16. The blade elements 14 and 16 in the die rule press here illustrated, and used in the present invention, are set in parallel relation to each other, and are elongated in configuration, and have a cutting edge 14a disposed at the upper side thereof in an exposed position to facilitate cutting through a substrate sheet as hereinafter explained.

The blade elements 14 extend substantially parallel to each other and, as depicted in FIG. 2, are arranged so that there are a plurality (four in the illustrated embodiment) of relatively short blade elements 14 which have their ends aligned inwardly of the outer edges of the wooden blocks 10. The relatively short blade elements 14 are positioned between relatively longer blade elements 16 disposed at the outer sides of the set of blade elements 14. Each pair of outer blade elements 16 and the intermediate, relatively short blade elements 14 located therebetween may be described as constituting an array, and it will be noted that in the portion of the die rule press depicted in FIGS. 1 and 2, one of the relatively long blade ele-

ments 16 may form a common outer blade element for a pair of contiguous arrays. It may also be seen in referring to FIG. 2 that the relatively long blade elements 16 which are disposed at the outer side of the intermediate blade elements 14 also do not extend all the way to the edge of the wooden spacer blocks 10 and that the relatively long blade elements also terminate with their ends in transverse alignment similarly to the transverse alignment of the opposite ends of the relatively short blade elements 14. Last, it will be noted that in the illustrated die rule press, the spacing between the several blade elements is uniform.

With the die rule press made up for use in the practice of the process of the present invention, the fibrous or synthetic resin substrate sheets which are to be severed by the die rule press are next prepared. A sheet of fibrous or synthetic resin material which has been provided with a pressure-sensitive adhesive on one side thereof and a printable surface on the other side thereof is passed through a silk screen printing apparatus, or other suitable printing means, to provide on the surface of the substrate material opposite that which carries the pressure-sensitive adhesive, a repeating pattern of some suitable type according to the aesthetic designs contemplated. For purposes of illustration only, repeating patterns of the type generally contemplated are shown in FIG. 3 where there is illustrated the surface of a fibrous substrate sheet 20 which has been subjected to the emplacement of a pattern on one surface thereof by a silk screening process. It will be noted that here four different repeating patterns have been produced on the printed surface of the substrate, these patterns being denominated by reference characters A, B, C, and D, and constituting, respectively, a pattern of repeating squares, a pattern of repeating hexagons, a pattern of repeating ellipses, and a pattern of repeating circles. As the sheet 20 has been printed in the example under consideration, the pattern of squares A has been repeated in five elongated columns in which the squares are aligned. The same is true of the hexagon pattern, B, the ellipse pattern, C, and the pattern of circles, D.

After the sheet has been printed in the manner described, the sheets are ready for slitting or severance along certain lines which will be formed according to the manner in which the die rule press has been made up. A plurality of the sheets 20 are stacked on top of each other or superimposed so that a number of the sheets may be cut through simultaneously. Such cutting through of a plurality of sheets by the use of a die rule press is known in the art. Having made up the die rule press in the manner shown in FIGS. 1 and 2, the sheets are then placed in either a flat bed press or a rotating drum press, and the sheets are brought against the sharpened upper edges of the blade elements 14 and 16, and pressure is applied to force the blade elements through the sheets to provide slits therein.

When the sheets 20 have been cut through in the manner described, the sheets then carry a plurality of relatively shorter elongated parallel slits 22 which correspond in number to the number of the relatively short knife elements 14. The relatively short slits 22 are disposed between relatively longer slits 24 which have been formed in the substrate sheets 20 by the relatively longer knife elements 16. When the process of slitting the superimposed sheets has been completed, each sheet has the appearance shown in FIG. 3. Thus, parallel slits are formed within the borders or peripheral edges of the sheet, and the sheet remains intact with a plurality of parallel contiguous strips being identifiable therein, and with each strip carrying a repeating pattern over its length. It follows from this result that the slits formed by the blade elements 14 and 16 have been formed between the aligned rows of the repeating figures so that each strip carries the repeating pattern within its borders formed by the slits.

After the sheets 20 have been slit in the manner described by the use of the die rule press, the superimposed sheets are removed from the press and are subjected to a further cutting

action using a guillotine blade or other suitable structure which is capable of cutting through a number of the sheets 20 when they are superimposed. The lines along which the sheets are cut in this step of the process are indicated in dashed lines 5 in FIG. 3, these lines being identified by reference numerals 28 and 30. It will be seen that by cutting the sheets along the lines 28 and 30, sections of the sheets become severed from each other. These sections correspond to the portions of the sheet which are defined between the relatively long slits 24 10 formed in the sheet by the relatively long blade elements 16.

By the severance of the sections of the sheets between the relatively long slits 24, there are provided a plurality of packages of strips, with these strips carrying the same pattern and being easily severable from the package due to the small 15 distance which separates the ends of the short slits 22 within each package from the edge of the strip formed after the sheets have been cut along the lines 28 and 30. The packages as thus formed are aesthetic in appearance, provide a relatively large number of lineal feet of total molding strip available to 20 the housewife or other purchaser, and facilitate much more ease in usage than rolls or other forms of package which have previously been used to market molding strips of this type.

Although a preferred embodiment of the invention has been herein described in order to exemplify one mode of practice of the method of the invention, it will be understood that various changes and innovations can be effected in the described procedure without departure from the basic principles of the invention. All changes and innovations of this type are therefore deemed to be circumscribed by the basic principles of the invention except as the same may be limited by the appended claims or reasonable equivalents thereof.

What is claimed is:

1. A method of forming a package of flexible molding strips comprising:

imprinting upon a surface of a flexible substrate sheet having an adhesive on the opposite surface thereof, a plurality of parallel, aligned columns of repeating decorative figures;

cutting through the sheet along parallel lines which terminate inside the outer edges of the sheet and extend between the parallel aligned columns of repeating figures, said lines being of two different lengths and forming a series of contiguous parallel line arrays to be formed into separate packages, each of said line arrays including a plurality of relatively short, parallel conterminous lines, and a pair of relatively long, parallel conterminous lines positioned on opposite sides of said relatively short lines, the opposite ends of said relatively long lines extending beyond the opposite ends of said relatively short lines, and all of said lines terminating inside the peripheral edges of said sheet; then

cutting said sheet along lines extending normal to, and intersecting, said relatively long lines and disposed between the ends of said relatively short lines and the peripheral edges of said sheet to form a plurality of packages having joined parallel strips of repeating figures thereon.

2. The method of forming a package as defined in claim 1 wherein said cutting is accomplished by:

placing a plurality of die rule cutting elements in an array corresponding to the lines to be cut through the substrate sheet; then

placing the die rule cutting elements in a press and pressing them against the substrate sheet to cut through the sheet.

3. The method defined in claim 1 wherein said imprinting is accomplished by silk screening the repeating decorative figures on the surface of the flexible substrate sheet.

4. The method defined in claim 1 wherein a plurality of said sheets are superimposed on each other after the imprinting step and during said first mentioned and second mentioned cutting steps.
